UNITED STATES PATENT OFFICE.

FRANK MCINTYRE, OF NEW YORK, N. Y., ASSIGNOR TO CHARLES J. TAGLIABUE,
OF BROOKLYN, NEW YORK.

CASING FOR CLINICAL THERMOMETERS.

1,041,135.

Specification of Letters Patent.

Patented Oct. 15, 1912.

Application filed September 8, 1911. Serial No. 648,349.

To all whom it may concern:

Be it known that I, FRANK MCINTYRE, a citizen of the United States, and a resident of the borough of the Bronx, city, county, 5 and State of New York, have invented certain new and useful Improvements in Casings for Clinical Thermometers, of which the following is a specification.

My invention relates more particularly to 10 devices for returning the mercury to the bulb of a clinical thermometer and has for its object to provide a device of this kind which may be easily and quickly operated to secure the desired results with a minimum 15 of danger to the thermometer.

In the preferred form of my invention the device is incorporated in and preferably forms part of the customary casing used for carrying and protecting a clinical thermo- 20 meter when not in use.

My invention will be fully described hereinafter and the features of novelty will be pointed out in the appended claims.

Reference is to be had to the accompanying 25 drawings in which—

Figure 1 is a longitudinal section of a thermometer casing used as a protecting and carrying medium and with my improvement applied thereto; Fig. 2 is a similar view 30 showing the thermometer in position to have the mercury returned to the bulb; Fig. 3 is an elevation of my particular device separated from the thermometer casing and Fig. 4 is a sectional view thereof on the line 4—4 35 of Fig. 3.

In the specific illustration of my invention shown in the drawings the casing comprises a tubular member 5, having opposite open ends, one of which is screw-threaded, 40 as indicated at 6 to receive the screw-threaded neck 7 of a cap 8 in which the one end of the thermometer 9 is rigidly secured. When the screw-threaded elements 6 and 7 are connected together as shown in Fig. 1 45 the thermometer extends axially within the casing, which thus serves as a protecting and carrying medium for said thermometer when not in use.

In the preferred form of my invention 50 my particular device extends into the opposite open end of the tubular member 5, and serves to close the same so as to form a bot-

tom for said tubular member. The device comprises a casing 10, having a frictional engagement with the inner surface of said 55 tubular member 5, and preferably held against movement relatively to said member 5, by means of roughened portions 11, shown best in Figs. 2 and 3. The interior end of the casing 10 is preferably closed and is provided with an axial opening 12, the purpose of which will be more fully described hereinafter. A sleeve 13 projects into the outer open end of the casing 10, so as to be rotatable relatively thereto, an annular flange 60 14, being provided on said sleeve for engagement with the end of the casing 10. This flange 14, in addition to limiting the inward movement of the sleeve 13 relatively to the casing 10, together with said casing 70 end, also serves as a bearing during any rotative movement of said sleeve. The free end of the sleeve 13, is closed and provided with an angular slot 15, through which passes the angular shank of a stem 16 formed 75 at one end with a head 17 arranged to abut against the closed end of the sleeve and having its opposite end passing through and rotatable in the opening 12 of the casing 10. This last named end of said stem after passing 80 through the opening 12 is turned over or spread as indicated at 18, and with the head 17 serves to prevent separation of the casing and sleeve in an axial direction. With this construction the sleeve 13 is secured 85 against rotative movement relatively to said stem, and with said stem is rotatable relatively to the casing. If desired, a washer 19 to take up wear may be located between the turned over or spread end 14, and the 90 closed end of the casing 10, although this is not absolutely necessary. The head 17 is provided with a thermometer holding means of any kind, as for instance an aperture 20, so that with this construction the sleeve 13 95 and stem 16 form what might be termed a thermometer carrying section. A coil spring 21 is located within the casing 10 and sleeve 13, and has its one end 22 secured to said casing and its other end 23 secured to the 100 sleeve 13.

In operation after the thermometer has been used in the customary manner and reading has been had, and it is desired to

return the mercury to the bulb of the thermometer the said thermometer 9 is first projected through the opening 20 of the head 17, with its axis extending at substantially 5 right angles to the axis of the casing. The tubular member 5 is now grasped in one hand, preferably with its axis extending in a horizontal direction and the thermometer tube depending from the head 17, the neck 10 7 in this position of the parts preventing the thermometer from slipping entirely through said opening 20. With the other hand the thermometer is now moved in a circular path to cause the stem 16 and the 15 sleeve 13, or in other words the thermometer carrying section to rotate about their common axis and relatively to the casing 10, which is rigidly held against rotation in the tubular section 5. This operation will cause 20 the spring 21 to be torsionally wound or twisted and thus cause it to exert a torsional stress upon the said sleeve 13 and stem 16. After a few turns the thermometer tube is released from the restraining influence 25 of the hand of the user, whereupon the spring 21 will immediately tend to unwind itself or in other words resume its normal condition. This unwinding of the said spring will cause said sleeve 13 to rapidly 30 rotate about its own axis in a direction opposite to that in which said sleeve was rotated to wind the spring and will rapidly whirl or swing said thermometer in a reverse circular path. The centrifugal force 35 generated during this rapid circular movement of said thermometer will cause the mercury to fly toward the tube or back to normal position, the neck 7 serving to prevent the thermometer from leaving the opening 20 during this operation. If the device 40 is operated as described it will be found that at the termination of the whirling movement just described the thermometer will again depend from the head 17, and will 45 thus be prevented from accidentally dropping from the opening 20 after the operation of returning the mercury to the bulb has been completed.

It will thus be seen that I provide a simple and easily operated device for returning the mercury to the thermometer bulb, which may be readily used by inexperienced persons with the danger of injury to the thermometer reduced to a minimum, and which 55 may be also used to great advantage by persons such as doctors, nurses, etc., who are experienced in the use of a clinical thermometer.

My improved device is very rapid in 60 action and brings the mercury back to a position to permit of the successive use of the thermometer in a very small period of time, thus making it possible to use the ther-

momter a great deal oftener in a given space of time than has been possible with the old method of shaking back the mercury.

While I have described my improved device as rigidly secured in a thermometer casing, the said device may be removably secured therein and removed each time it is desired to return the mercury to the thermometer bulb. In addition to this, the device instead of being inserted into the tubular member 5, may be inserted into the cap 8 which in this case would be provided with a recess for removably receiving said device. Furthermore, the said device might be made as a separate article and used as an auxiliary to the ordinary thermometer case in which instance it would look like the illustration 80 shown in Fig. 3. If used in this manner, the casing 10 would be held in the one hand of the user during the winding of the spring and the whirling or swinging of the thermometer.

The spring 21 in addition to its other functions also serves to maintain the sleeve in position in the casing and the flange 14 in contact with the end of said casing, both during the operation of the device and while the parts are at rest.

Various changes may be made in the specific forms shown and described within the scope of the claims without departing from the spirit of my invention.

I claim:—

1. A device for returning the mercury to the bulb of a thermometer, comprising a tubular member, a casing extending into the one end of said member, a thermometer carrying section rotatably mounted in said casing and having means for removably connecting a thermometer therewith, and means connected with said casing and said thermometer carrying section respectively for 100 rotating said section relatively to said casing.

2. A device for returning the mercury to the bulb of a thermometer comprising a tubular member, a casing extending into the one end of said member, a sleeve rotatably mounted on said casing, a stem rigidly connected with said sleeve and provided with means for holding a thermometer, said stem being rotatably secured to said casing and 115 means connected with said casing and said sleeve for rotating said sleeve and stem relatively to said casing.

3. A device for returning the mercury to the bulb of a thermometer comprising a 120 tubular member, a casing extending into the one end of said member to close the same, a sleeve rotatably mounted on said casing, a stem passing through said sleeve and said casing and being rigidly connected with the 125 sleeve and rotatably secured to the casing,

the one end of said stem being provided with an aperture for holding a thermometer and a spring connected with said casing and said sleeve and arranged to be wound to exert a torsional stress on said sleeve and said casing and to rotate said sleeve and stem relatively to the casing when released.

In testimony whereof, I have hereunto set my hand in the presence of two subscribing witnesses.

FRANK McINTYRE.
